US00D523397S

(12) **United States Design Patent**
Maglionico et al.

(10) Patent No.: **US D523,397 S**
(45) Date of Patent: **** Jun. 20, 2006**

(54) **RECHARGEABLE BATTERY PACK FOR
PROVIDING UNINTERRUPTED POWER**

(76) Inventors: **Richard Maglionico**, 175 Pine Cone Dr., Lehighton, PA (US) 18235; **Sharyl J. Maglionico**, 175 Pine Cone Dr., Lehighton, PA (US) 18235

(**) Term: **14 Years**

(21) Appl. No.: **29/215,021**

(22) Filed: **Oct. 14, 2004**

(51) LOC (8) Cl. **13-03**

(52) U.S. Cl. **D13/137.2**

(58) Field of Classification Search D13/123, D13/133, 137.1-139.8, 160; 174/48-49, 174/53-58; 439/105-107, 535-536, 650-655, 439/692

(57) **CLAIM**

The ornamental design for a rechargeable battery pack for providing uninterrupted power, as shown and described.

DESCRIPTION

FIG. 1 is a front elevational view of a rechargeable battery pack for providing uninterrupted power showing our new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a perspective view thereof.
